UNITED STATES PATENT OFFICE.

CLARENCE W. BENNETT, OF NEW YORK, N. Y., ASSIGNOR TO ARDEN-BENNETT CORPORATION, OF NEW YORK, N. Y., A CORPORATION OF NEW YORK.

DESIGN FOR A TOY AUTOMOBILE.

56,800.

Specification for Design.

Patented Dec. 28, 1920.

Application filed January 19, 1920. Serial No. 352,622. Term of patent 3½ years.

To all whom it may concern:

Be it known that I, CLARENCE W. BENNETT, a citizen of the United States, residing at New York city, New York, have invented a new, original, and ornamental Design for a Toy Automobile, of which the following is a specification, reference being had to the accompanying drawing, forming a part thereof.

The figure is a side elevational view of a toy automobile showing my new design.

I claim:—

The ornamental design for a toy automobile, as shown.

CLARENCE W. BENNETT.
